(57) **CLAIM**

We claim the ornamental design for the portion of headset with optical display element, as shown and described.

DESCRIPTION

FIG. 1 is a front perspective view of a portion of headset with optical display element showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the portion of headset with optical display element of FIGS. 1–8 shown with selected disclaimed features removed for clarity;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken line showing of the remainder of the optical display element for a headset is for environmental purposes only and forms no part of the claimed design. The figures feature transparent visor portions through which other features are visible. FIGS. 9 through 16 show the optical display element for a headset of claims 1–8, with selected disclaimed features removed for clarity.
